(57) **CLAIM**

The ornamental design for a confectionery product with drip catching dipper and cup, as shown and described.

DESCRIPTION

FIG. 1 is a top perspective view of a confectionery product with a drip catching dipper and cup showing my new design; FIG. 2 is a front elevational view thereof, the rear elevational view being identical thereto; and

FIG. 3 is a right side elevational view thereof, the left side elevational view being identical thereto.

FIG. 4 is a top plan view thereof; and,
FIG. 5 is a bottom plan view thereof.

The broken lines showing the cover in FIGS. 1-3 are for illustrative purposes only and form no part of the claimed design.
